FRANK E. STOVER, OF SPRINGFIELD, OHIO, ASSIGNOR OF ONE-HALF TO DENNIS T. IGOU,
OF SPRINGFIELD, OHIO

CIRCUIT MAKER AND BREAKER

Application filed June 10, 1929. Serial No. 369,538.

This invention relates to circuit makers and breakers, it more particularly relating to devices of this kind which are thermostatically controlled.

5 One of the objects of my invention is to provide a circuit maker and breaker which will be simple in construction and effective in operation.

10 Another object of the invention is to provide an arrangement by which the contact points are positively opened and closed by thermostatically controlled mechanical means operated by a continuously moving part.

15 Further objects will appear from the accompanying description and claims.

In the accompanying drawings:

Fig. 1 is a side elevation of a circuit maker and breaker embodying my improvements.

20 Fig. 2 is a front elevation of the same.

Fig. 3 is a top plan view of the same.

Fig. 4 is an enlarged sectional view on the line 4-4 of Fig. 2.

25 Fig. 5 is an enlarged fragmentary view in perspective of the continuously movable operating member.

The invention has been devised particularly to control the temperature of incubators, although it is not necessarily limited to that particular purpose. In incubators of the so-called mammoth type, it is usual to employ a fan to induce a forced draft of air through the incubators, the fan being continuously operated from any suitable source 30 of power. In one type of incubator, an electric heater is employed to heat the air which is circulated through the incubator by the fan, the temperature of the air being controlled by a thermostat which opens and 35 closes the circuit of the heater at suitable intervals. In carrying out my invention, I make use of the continuously rotating fan shaft as the member which operates the contact opening and closing means, although it is to be understood that any other suitable continuously movable member may be employed if desired. Such a shaft is indicated 40 at 1 and it is sufficient to say that the shaft 45 is continuously rotated while the incubator

is in operation from any suitable source of power.

The contacts to be opened and closed are indicated at 2 and 3 and in the present case the contact 2 is movable and the contact 3 stationary. The contact 2 is secured to a block 4 of insulating material which is carried by a bifurcated metallic arm, the parts of which are indicated at 5, which is pivotally mounted on screws 6, inserted in a frame which carries at its upper portion another insulating block 7 to which the stationary contact 3 is secured. The circuit is made when the movable switch arm is swung to the position shown in broken lines in Fig. 2 and the arm will be held in either on or off position by the action of the coiled spring 8, one end of which is hooked to a cross pin 9 carried by the upper end of the arm and at its lower end hooked to a bar 10 carried by a downward extension of the frame.

A flat lever 11 is pivotally hung from the rod 13 and has its lower end provided with a fork, the tines 12 and 12' of which are offset and straddle the shaft 1; the pivoted end of the lever being confined against axial movement on the rod 13 by a pair of collars 16. The rod 13 is carried by a ring 15 which is supported by a U-shaped bracket 17 mounted at any convenient point but in such a way that the tines 12 and 12' of the fork may be conveniently caused to straddle the shaft. By this manner of mounting the lever 11 it will be seen that it is free to swing like a pendulum from the rod 13 but only in a plane perpendicular to the rod. The mounting of the ring 15 in the bracket is by means of trunnion screws 19, threaded in diametrically opposite openings in the ring and fitting loosely in the ears 17' of the bracket. These trunnions are at right angles to the axis of the rod 13 and allow the lever to swing to and fro in a plane parallel to the axis of the shaft 1, while the pivoted connection of the lever with the rod 13 allows the lever to swing in a plane at right-angles to the axis of the shaft 1, the effect being to so support the lever 11 that it may have a universal movement with respect to the shaft.

The shaft 1 is provided with a laterally

100

projecting pin 20 which is so positioned as to rotate in the space between the offset tines 12 and 12' when the lever 11 is depending in the neutral position. It will be clear, therefore, 5 that if the ring 15 is rocked on its trunnions to a sufficient degree, one or the other of the tines 12 and 12' will be brought in the path of the pin 20, engaged thereby at one point of its rotation, and the lever 11 swung in 10 a plane at right angles to the axis of the shaft. The lever 11 has a connection with the moveable switch arm 5 by means of an extension 21 on the lever which terminates in a hook 22 which hangs over a cross bar 23 15 carried by the arm 5, so that when the lever 11 is rocked by the pin 20 in either direction the switch arm 5 will be moved correspondingly to open or close the switch.

The ring 15 is rocked to effect this operation by the action of a thermostat T, shown 20 in the present case as a thermostat of the wafer type, which is pivotally connected by a link 24 with a pivoted arm 25 which in turn is connected by a link 26 with the arm 13. 25 The thermostat is placed at any suitable point where it will be responsive to the temperature of the air which is heated by the electric heater, shown in the present case as an ordinary resistor R in the circuit controlled by the contacts. 30

The pin 20 is shown in an enlarged partial perspective view in Fig. 5. The outer extremity is formed in a manner to insure engagement with the tines 12 or 12' at such 35 times as when, during the swing of the lever 11, the tines are merely approaching the path of the pin 20. At each corner a projection 27 is formed by rounding of the portions between. These projections engage a shallow 40 V-groove 28 recessed in similar positions in the tines 12 and 12', being, in each case, in the free end of the tine near the corner adjacent the path of the pin 20. As the shaft further revolves, the flat end portion 20' engages the flat inner surface of either of the 45 tines, and the lever 11 may therefore have some lateral movement, since the projections are not at this time engaged in the grooves 28. This is desirable, as it tends to prevent 50 undue strains on the thermostat or the connections, which are normally in constant movement.

To insure a good contact, the stationary contact 3 is preferably arranged to yield 55 against the tension of a coil spring 29 which is interposed between the said contact and head of a screw 30 inserted in the supporting bracket 7.

Having thus described my invention, I 60 claim:

1. In a circuit maker and breaker, a movable contact member, a continuously moving member, and intermediate connections between said contact member and continuously 65 moving member for positively actuating said

contact member to either open or closed position, together with thermostatic means for placing said connections and said continuously moving member in operative relation with each other at predetermined changes in temperature to cause said contact member to either make or break an electric circuit. 70

2. In a circuit maker and breaker, a pair of relatively movable contact members, a continuously moving member, an intermediate 75 connection between said continuously moving member and one of said contact members for positively actuating said contact member from said continuously moving member to either closed or open relation with said other 80 contact member, and thermostatic means for placing said continuously moving member and said intermediate connection into operative relation with each other at predetermined changes in temperature. 85

3. In a circuit maker and breaker, a movable contact member, a continuously rotating member, movable intermediate connections between said members having a pair of offset 90 projections, and thermostatic means for placing either one of said offset projections and said continuously rotating member into operative relation with each other at predetermined changes in temperature. 95

4. In a circuit maker and breaker, a movable contact member, a continuously rotating member, movable intermediate connections between said member having a pair of offset 100 projections one on each side of the axis of rotation of said continuously rotating member and thermostatic means for alternately placing said continuously rotating member and one of said projections into operative relation with each other at predetermined changes in temperature. 105

5. In a circuit maker and breaker, a movable contact member, a continuously rotating member, a thermostatically controlled member for actuating said contact member having a pair of offset projections one on each side 110 of the axis of rotation of said rotating member, said thermostatically controlled member being movable in a plane parallel with the axis of rotation of said rotating member and also movable in a plane at right angles to the axis of rotation of said rotating member. 115

6. In a circuit maker and breaker, a movable contact member, a continuously rotating projection, a thermostatically controlled member for actuating said contact member having offset portions arranged one on each side of the axis of rotation of said projection and movable in planes parallel with the axis of rotation of said projection to bring either one of said offset portions into the path of said projection, said thermostatically controlled member being also movable by said projection in a plane in right-angles to the rotation of said projection.

7. In a circuit maker and breaker, a movable contact member, a continuously rotating projection, a thermostatically controlled arm connected with said contact member, said arm having offset portions arranged on either side of the axis of rotation of said projection, a support to which said arm is pivotally connected to permit the arm to swing in a plane at right-angles to the axis of rotation of said projection, said support being pivotally mounted to swing said arm in a plane parallel with the axis of rotation of said projection, and temperature responsive means for rocking said support.
8. In a circuit maker and breaker, a pivoted contact arm, a continuously rotating projection, an operating arm connected with said contact arm, a pivoted support to which said operating arm is pivotally connected, the pivot for the support being such as to permit said operating arm to swing in a plane parallel with the axis of rotation of said projection, the pivotal connection of said operating arm with said support being such as to permit the operating arm to swing in a plane at right-angles to the axis of rotation of said projection, temperature responsive means connected with said support, and offset projecting portions on said operating arm arranged on opposite sides of the axis of rotation of said projection.
9. In a circuit maker and breaker, a pivoted contact arm, a continuously rotating projection, a ring-like support pivoted on an axis at right-angles to the axis of rotation of said projection, an operating arm pivoted to said ring-like support on an axis permitting the arm to swing in a plane at right-angles to the axis of rotation of said projection, temperature responsive means connected with said support to rock the same about its axis, and a pair of offset fingers connected with said operating arm and straddling the axis of said projection.
10. In a circuit maker and breaker, a continuously rotating arm, the free end of which is channeled to form sharp projections at the sides thereof, a thermostatically controlled member having a pair of offset fingers straddling the axis of rotation of said projection, each of said fingers having a groove on that side thereof adjacent the path of said arm having a sharp side wall, for the purpose specified.
11. In a circuit maker and breaker, a single movable contact member, a continuously rotating member, a movable intermediate member operated by said continuously rotating member for actuating said contact member to either open or closed position, and thermostatically controlled devices for placing said rotating member and intermediate member into operative relation with each other to cause said intermediate member to be moved in either one direction or the other, the movement of said intermediate member under the action of said rotating member serving to place the same out of operative relation with said rotating member.
12. In a circuit maker and breaker, a movable contact member, a continuously moving member, a thermostat, an intermediate device adapted to form a connection between said continuously moving member and said contact member to actuate said contact member to both open and closed position, and means mechanically controlled by said thermostat for placing said continuously moving member and said intermediate device in operative relation with each other at predetermined changes in temperature to cause said contact member to make or break an electric circuit.
13. In a circuit maker and breaker, a movable contact member, a continuously rotating member, an expansible and contractible thermostat, an intermediate connection between said rotating member and contact member for positively actuating said contact to open or closed position, and devices mechanically operated by said thermostat to bring the rotating member and the intermediate connection into the same path at predetermined changes in temperature to cause the intermediate connection to be operated by said rotating member.
14. In a circuit maker and breaker, a contact member, a continuously moving member, an expansible and contractible thermostat, an intermediate connection for positively actuating said contact member to open or closed position having a to and fro movement, and devices mechanically actuated by said thermostat for bringing said continuously rotating member and separate portions of said intermediate connection into the same path to cause said rotating member to move said connection in either one direction or the other to thereby actuate said contact member to open or closed position.
15. In an electric switch, a movable contact member, a continuously rotating member, means for moving said contact member by said continuously rotating member to either open or closed position to maintain the circuit of which it is a part either open or closed until said contact member is again operated, and thermostatic means for placing said continuously rotating member and said contact moving means in operative relation.
16. In an electric switch, a pair of contact members for controlling the main electric circuit adapted to maintain said circuit either closed or open in accordance with temperature conditions, one at least of said contacts being movable, a continuously rotating member, means actuated by said rotating member for positively opening or closing said movable contact member, and thermo-

statically controlled means for placing said rotating member and contact operating means in operative relation.

17. In an electric switch, a movable contact member, a continuously rotating member, means for moving said contact member by said continuously rotating member comprising a part located on each side of the axis of rotation of said rotating member, and 10 thermostatic means for placing said continuously rotating member and said parts of said contact moving means alternately in operative relation.

In testimony whereof, I have hereunto set 15 my hand this 27th day of May, 1929.

FRANK E. STOVER.
